[57] ABSTRACT

A flechette small caliber projectile providing tracer visibility capability during flight while ballistically trajectory matching a small caliber ball flechette and retaining a high velocity low drag profile. Tracer material is located in a rearwardly opening internal cavity provided in the flechette projectile cylindrical body portion. Fin stabilizers surround or extend radially outward of the tracer cavity.

1 Claim, 2 Drawing Figures

1
PROJECTILE

The invention described herein may be manufactured, used and licensed by or for the Government for governmental purposes without the payment to us of any royalty thereon.

This invention relates to projectiles, and more particularly to a small caliber flechette-type projectile.

It is an object of the invention to provide a small caliber flechette projectile having tracer visibility capability during its flight.

Another object of the invention is to provide such a projectile that will have ballistic trajectory equivalent to that of a small caliber ball flechette projectile.

A further object of the invention is to provide such a projectile that retains a high velocity low drag profile.

These and other objects, features and advantages will become more apparent from the following description and accompanying drawings in which:

FIG. 1 is an elevational view, partially broken away in section, of a preferred projectile embodying the principles of the invention.

FIG. 2 is a sectional view taken along lines 2—2 of FIG. 1.

The small caliber flechette projectile, shown generally at 10 (FIG. 1), has a forward nose portion 11 and a substantially cylindrical rearward portion 12 (FIGS. 1, 2) carrying a plurality of fin stabilizers 13 at the rearmost end of the projectile. Surrounding the forward portion of the projectile, particularly at the tapered nose 11, is a plurality of segmental sabot portions 14 held in pre-flight position by an appropriate rubber sealing ring 15. The sabot has its own tapered nose and, after the projectile is fired from a suitable gun muzzle, its multiple segmental portions 14 are released and rapidly fall away from the projectile due to the operative expanding and rupturing of sealing ring 15.

Preferably, the fin stabilizers 13, which extend substantially radially outward from the rearward end of cylindrical portion 12, are each formed to incline at a slight angle (approximately 1.5°) to the longitudinal axis of the projectile to facilitate imparting spin to the launched projectile.

The projectile cylindrical portion 12 is provided with a rearwardly opening, longitudinally extending, drilled internal tracer cavity 16 in which is located, preferably,

2

an elongated tube 17 of tracer material 18 and a somewhat shorter length of tubing 19 containing igniter material 20 (FIG. 2). The igniter tube 19 is located at the rearward end of the cavity 16 and held in position therebetween by an appropriate deforming action provided on the rearmost end of the then filled hollow cylindrical portion 12. The preferred means of deforming the rearward end of cylindrical portion 12 is by crimping with an appropriate crimping tool positioned at predetermined peripheral locations between rearmost portions of adjacent ones of the outwardly extending fins 13. Preferably, the projectile cylindrical portion 12 has an external diameter of 0.1 inches, its cavity 16 has a recessed or drilled surface diameter of 0.06 inches, and the span across a pair of substantially diametrically opposed fins 13 is 0.2 inches.

Various modifications, changes or alterations may be resorted to without departing from the scope of the invention as defined in the appended claims.

We claim:

1. In a flechette projectile arrangement having a substantially pointed forward nose portion, a substantially cylindrical rearwardmost portion, and an intermediate substantially cylindrical portion, said rearmost portion having a diameter greater than that of said intermediate portion, said cylindrical rearwardmost portion having a plurality of fin stabilizers extending radially outward therefrom and a rearwardly opening longitudinally extending internal tracer cavity, said cavity having a forward wall located rearward of said intermediate cylindrical portion, a tube of tracer material in said cavity, a multiple segmented sabot surrounding said nose portion, a rupturable rubber sealing ring surrounding the multiple segmental sabot, each of said fin stabilizers extending in a direction inclined to the longitudinal axis of said projectile, and means, including an igniter tube in a rearward end of said cavity of said cylindrical rearmost portion and longitudinally aligned rearwardly of said tracer tube, for retaining said tracer tube in said cavity.
